UNITED STATES PATENT OFFICE.

FRANK S. RECE, OF DALLAS, TEXAS.

ADJUSTABLE CRIB OR BED.

1,322,616.

Specification of Letters Patent. Patented Nov. 25, 1919.

Application filed May 11, 1918. Serial No. 233,867.

To all whom it may concern:

Be it known that I, FRANK S. RECE, a citizen of the United States, residing at Dallas, in the county of Dallas and State of Texas, have invented certain new and useful Improvements in Adjustable Cribs or Beds, of which the following is a specification, reference being had to the accompanying drawings.

10 This invention relates to cribs or beds for children, and more particularly to those beds or cribs which are designed to be drawn up beside the main bed on which the mother of the child sleeps.

15 The general object of this invention is to provide a crib or child's bed as above referred to, which is easily and quickly attachable to or connected with any make of adult's bed of whatever reasonable height 20 so that the mattresses of the bed and crib will be perfectly even or flush, without space or obstruction between them.

A further object is to provide a bed of this character which is adjustable as to 25 height so that the mattress of the child's bed may be placed on an exact level with the mattress of the mother's bed and the means for this purpose being such as to eliminate any danger of the bed shifting after having 30 been adjusted.

A further object is to provide a bed of this character with wheels and to provide a brake for the wheels so that the crib may be held stationary in any desired position, the brake 35 being easily releasable to permit the crib to be shifted and to be wheeled about.

A further object is to provide improved means for engaging the child's bed with the mother's bed without in any way marring 40 the side rail of the mother's bed.

A further object is to so construct the bed that it may be "knocked down" or collapsed so as to facilitate shipping.

Still another object is to provide a crib 45 with side rails, one wall of the crib composed of these rails being hinged so that it may be turned down and being also adapted to be shifted on supporting rails beneath the mattress of the crib and out of the way.

50 Other objects will appear in the course of the following description, and have to do with the detailed construction of the bed,

whereby it may be cheaply made and easily handled.

My invention is illustrated in the accompanying drawings, wherein:—

Fig. 1 is a side elevation of my improved adjustable crib;

Fig. 2 is a vertical sectional view of the 60 crib;

Fig. 3 is an end elevation thereof;

Fig. 4 is an enlarged sectional detail view through one of the axles showing the brake;

Fig. 5 is a fragmentary end elevation showing the crib in conjunction with a bed; 65

Fig. 6 is a fragmentary vertical section on the line 6—6 of Fig. 1;

Fig. 7 is a sectional view through the 70 axle 10 showing the elevating ratchet in elevation;

Fig. 8 is a fragmentary perspective view of the outer end of one of the rails 15;

Fig. 9 is a detail fragmentary plan view of the rails 15 and 21^a at their junction;

Fig. 10 is a front elevation of the 75 construction shown in Fig. 9;

Fig. 11 is a fragmentary vertical sectional view through one of the supports 37 and the longitudinally extending members 36; and

Fig. 12 is a detail perspective view of the 80 member 40.

Referring to the drawings, it will be seen that the body of the crib comprises the end supporting members 10 and the longitudinally extending side supporting members 85 11 and 12, which are connected to each other in any suitable manner and may be made of any suitable material. Extending upward from the end supporting members 10 and from the side supporting member 12 90 are the rods 13 carrying the longitudinal rail 14 and the end rails 15, thus providing open walls on three sides of the crib extending upward to any suitable height to prevent the child's falling out of the crib. 95 Mounted upon each end member 10 is a transverse mattress supporting iron 16 upon which the spring mattress 17 is disposed and upon this spring mattress the usual mattress 18 rests. It will be noted that the 100 transverse end members 10 extend below the rails 11 and 12 and disposed below the members 10 are the transversely extending rails 19. These rails are formed of strips

of metal bent over the ends of the members 10, as at 20, and attached to the members 10 by means of screws, bolts or in any other suitable manner.

5 The rails 19 are spaced from the under faces of the members 10 for a purpose which will be now stated. Three sides of the crib, as previously stated, are formed with the upwardly extending fixed walls and 10 the fourth side is closed by means of a hinged wall 21 also formed of a rectangular frame having vertical rods. One longitudinal member of this frame is provided with the laterally projecting trunnions 22 which 15 extend into the space between the rails 19 and the under face of the members 10. It will thus be seen that these trunnions constitute pivots upon which the hinged wall 21 may turn and when the hinged wall is 20 turned to a horizontal position, it may be slid into a position beneath the main frame of the bed, this hinged wall being supported in this position by lugs 23 projecting from the rail 19. The hinged wall is held in its 25 retracted position by means of a spring latch 24 consisting of a strip of light spring metal attached to the under face of the rail 12 and twisted so that the free portion of the latch extends vertically, the free end 30 of the latch being beveled and formed with a small tooth adapted to engage over a metallic rib 25 attached to the inner rail of the hinged wall. This spring latch 24 is 35 relatively light so that the hinged wall may be readily pulled out from its engagement with the latch.

When the hinged wall is in place the stop lugs 26 bear against the rail 11 so as to prevent any further inward movement of 40 the hinged door. When the hinged door is in a vertical position, these lugs 16 rest within keepers 27 carried on the outwardly projecting end rails 15. These keepers 27 are provided by a strip of metal 28 illustrated in Fig. 8, which is bent downward 45 as at 29 over the end of the rail 15 and beneath the rail and which is provided with the lateral lugs, one of which, 30, extends down against the outside face of the rail 15 50 and is attached thereto. The other lug constitutes the keeper 27. The portion 29 also constitutes a keeper for engagement by a corresponding bolt 31, slidably mounted upon the extremity of the rail 21^a. This 55 bolt is mounted within a metallic strip 32 attached to the end of the rail 21^a and having lugs 33 bearing against the inner face of the rail, the body of the strip being spaced from the rail 21^a sufficiently to permit 60 the insertion of the bolt. The bolt is provided with a finger piece which projects down between these inwardly turned lugs 33. I do not wish to be limited to this, as it is obvious that other forms of bolts may 65 be used for the purpose of locking the

swinging wall of the crib in its vertical position.

For the purpose of supporting the body of the crib, I provide a pair of axles 34, these axles being non-rotatable and mounted 70 upon the ends of the axles are the wheels 35. These axles are connected by longitudinal members 36 which are attached to the axles in any suitable manner, and project beyond the axles a distance slightly 75 greater than one-half the diameter of the wheels and are preferably made of light angle iron. Formed integral with these longitudinal members 36 or attached thereto are the upwardly extending supporting members 37 which are longitudinally slotted as at 38. These supporting members 37 coat with adjusting screws 39 which extend through the slots 38, through the end beams 10 and engage with screw plates on the inside surfaces of the end beams 10, these adjusting screws preferably having relatively wide contacting faces in engagement with the face of the members 37. The upper ends of the members 37 are slidably 90 engaged by lateral guides, one of which is illustrated in Fig. 12, these guides being formed by a strip of metal 40 attached at its ends to the face of the corresponding beam 10, this strip being struck out to provide the 95 outwardly projecting lugs or ears 41 spaced from each other to receive between them the corresponding member 37. Thus the body of the crib is guided on the supporting members 37 and prevented from lateral 100 movement. The supporting members 37 are also provided with the outwardly projecting stops 42, which limit the downward movement of the body of the crib.

Preferably the members 37 are separate 105 from the longitudinal beams 36 and to this end the extremity of the longitudinal beam 36 is upwardly bent as at 43 and the member 36 is slotted as at 44. The member 37 is formed with a tongue 45 which is inserted 110 in this slot 44 and bent upward against the under face of the member 36. A metallic clip 46 embraces the upwardly turned portion 43 and the base of the member 37 115 and holds them in engagement with each other, but by sliding this clip 46 up the member 37 the parts may be disengaged so as to permit the parts to be separated from each other for packing. This is a preferable 120 construction of my invention, but I do not wish to be limited to this.

While I have shown means for vertically adjusting the body of the crib relative to the wheeled supporting frame upon which the crib is mounted, preferably the members 125 37, together with the screws 39, constitute guides and safety devices and the bed is actually held in its vertically adjusted positions by means of the curved ratchet toothed bars 47 disposed one at each end of 130

the crib. Each of these bars is downwardly and inwardly curved and has ratchet teeth on its under face and at its upper end each bar is formed with laterally projecting ears 48 5 formed at their ends to provide knuckles 49 engageable with a transversely extending pintle 50, which is fixed to the corresponding end rail 10. The middle portion of the upper end of the bar 47 is outwardly bent 10 to provide a handle 51. Each of these bars 47 passes through a vertically slotted eye 52, each attached to one of the axles 34, the lower wall of the slot in this eye being engaged by the ratchet teeth on the bar 47, 15 the bar falling into this engagement by gravity.

Now it will be obvious that when the bars 47 are engaged with the lower end of the slot in the eye 52, the crib will be supported 20 in its elevated position but assuming that the screws 39 are loose then upon depressing the handle 51, the corresponding bar will be elevated to carry its tooth out of engagement with the wall of the eye and the crib 25 will lower of its own weight. As soon, however, as the locking bars 47 are released they will again engage their respective eyes and hold the crib in its elevated position. If it is desired to raise the crib, it is only necessary to pull up on the crib and then the locking bars will shift through the eyes, the ratchet teeth riding over the lower ends of the eyes until the proper elevation has been reached, when they will automatically engage 30 with the eyes to hold the crib supported.

Adjusting the height is best accomplished by raising or lowering one end of the crib at a time though of course it is obvious that both 40 ends of the crib may be raised or lowered coincidently. After the proper height has been secured, which very largely depends upon the height of the adult's bed, the set screws 39 are firmly set to hold the bed body 45 stationary at this height where it will remain at all times unless a change of height is desired.

For the purpose of holding the crib in intimate proximity to the adult's bed, I provide 50 the engaging hooks 53. These have their bills extending downward and have shanks extending downward parallel to the bill, these shanks at their lower ends being upwardly turned as at 54 and passing upward through a bead 55 formed upon the end of the strip forming the rail 19, the upper end of the shank 54 being overturned as at 56 so as to prevent the shank from escaping 55 from the bead. The body of the hook is 60 preferably covered with India rubber tubing 57 so that the hook will not mar the rail of the bed with which it is engaged. The operative positions of the hooks are illustrated in Fig. 5, and in their inoperative positions the hooks are raised to their fullest 65 extent until the lower ends of the shanks engage with the lower ends of the bead 55 and the hook is turned so as to be disposed upon the rest 58 which is adjacent one end of the metallic member 40. Thus the hooks are 70 out of the way and disposed flat against the ends of the crib.

The wheels are provided so that the crib may be readily moved from place to place but it is, of course, desirable to lock these 75 wheels when the bed is at rest so as to prevent any movement of the bed. To this end I mount upon one of the axles 34 a brake engaging with the corresponding pair of wheels. This brake comprises the transversely extending brake rod or what might be termed brake beam 59. Adjacent its ends this brake beam is cranked as at 60 and engaged with ears 61 projecting from the axis. Thus this brake beam or rod may 80 swing toward or from the corresponding wheels 35. Pivoted to the under face of the axle 34 is a member 62, which constitutes a lever, this member being made of sheet metal having outwardly bent parallel sides. 90 Through these parallel sides passes a pintle 63 and a U-shaped yoke 64, the extremities of which are connected to the brake bar 60. The axle is cut-away as at 65 to accommodate the lever when it is turned to its operative position as illustrated in Fig. 4. When it is so turned the yoke 64 will be drawn outward, thus bringing the brake rod or beam to bear against the wheels 34 and it is held in this position by the fact that the 100 cross bar of the yoke passes the pivotal center of the lever as illustrated in Fig. 4. The lever projects slightly out beyond the axle so that a touch of the foot will release the lever and permit the brake bar to rotate 105 in its bearings to swing its ends away from engagement with the wheels.

It will be seen that I have provided, in the first place, a crib in which the height of the bed, that is, the crib body, is adjustable relative to the supporting wheels, and further in which the opposite ends of the crib are independently adjustable so that the body of the crib may be inclined, if desired or made absolutely level, and that further I have 110 provided a crib which, because of its wheels, may be readily shifted from place to place. This crib is to be made ordinarily from 22 to 26 inches wide and from 36 to 40 inches long, though, of course, it may be of any 115 desired size so as to pass easily through any ordinary doorway and the crib is of such light weight that it may be as easily wheeled about as a baby carriage. Thus it may be 120 taken into any room, onto a porch, or out of doors. It may be used as a perambulator, if desired or as an ordinary crib, either outdoors or indoors. It will also be obvious 125 that the swinging wall of the crib may be locked in its vertical position to thus pre- 130

vent the child from climbing out of the crib or that it may be readily unlocked and swung down so as to permit access to the child.

5 The most important function of my improved crib is that by properly manipulating the adjusting mechanism for the crib, the body of the crib may be positioned, so as to bring the mattress of the crib in exact 10 alignment or flush with the mattress of the adult's bed and that then the side of the crib, with the side wall turned down and slid beneath the body of the crib, may be locked to the side rail of the adult's bed. 15 Thus the child is placed in immediate proximity to its mother during the night or at any other time, but not in the same bed, the crib serving as a railed in extension of the 20 large bed and on an exact level with it and where the child is absolutely safe. The child 25 can be kept covered, drawn to its mother's side to nurse, replaced and otherwise attended to, without hindrance or obstruction arising from the bed in order to attend to the child's wants.

The attaching hooks move up and down in their sockets or beads, thus providing for any reasonable difference in the thickness or 30 depth of the two mattresses, springs, etc., on the two beds, thus rendering it possible at all times to have the mattresses exactly flush or even at their tops. The mattress and spring of a large bed will often be found to be 35 thicker or higher than that of a baby's bed or crib and it is for the express purpose of taking care of this that these hooks work up and down and further permit the hooks to be raised and then moved downward into 40 engagement with the rails of the large bed. The rail hooks attach equally well to angle iron or to the broad flat wooden rail of a wooden bed, in neither case marring or scar- 45 ring the bed by reason of the rubber covering of the hooks, this rubber covering also preventing any squeaking or rattling of the hook between the bed rail with which it is engaged.

In the morning or whenever desired, the 50 baby's bed or crib may be as readily detached from the main bed, the hooks re- 55 stored to their rests, the swinging side wall raised and engaged in its vertical position and the crib is ready to be wheeled any- 60 where. Of course it is to be understood that the wheels must be of small enough diameter to make it possible to attach the crib to the lowest railed adult bed manufactured. In other words, the lower ends of 65 the slots 38 must be low enough to permit this extreme lowering of the body of the crib while the uprights 37 may be of any height required.

It will be also noticed that the crib is 65 capable of being collapsed or "knocked

down." Thus by removing the four set screws 39, the body of the bed is readily lifted from the running gear, which lifting of the body of the bed releases the ratchet head bars 47 from their engagement with the axles. Then by rotating these arched supports it is possible to withdraw the beads 49 from their engagement with the pindle 50. The four slotted uprights 37 may now be disengaged from the members 70 75 80 85 90 95 100 105 110 115 120 125 130 36 in the manner heretofore described and the wheels may be removed and if further disassembling is desired, the two longitudinally extending beams 36 may be removed from the axles as they may be bolted upon the axles. This reduces the running gear to a few simple parts which may be readily packed, and it is obvious that the ordinarily fixed sides of the crib may be provided with hinges so that they may be folded down upon the mattress or may be entirely detached from the beams 10 and 11. I have not illustrated this, however, as this is a relatively simple matter which would be obvious to any manufacturer, and I do not believe it to be particularly desirable. The attaching hooks 52 are also preferably detachable from their sockets (not illustrated). It will be noted that the adjustment of the crib or bed is accomplished very simply and easily, without the necessity of using tools for the purpose.

While I have illustrated certain details of construction and arrangement of parts which I believe to be preferable, it is obvious that many modifications may be made in the construction, without departing from the spirit of the invention as defined in the appended claims, and likewise it will be obvious that the crib may be made in various styles and dimensions and that it may be made out of any suitable materials. Furthermore it will be seen that it may be relatively cheaply manufactured, considering the improved action of the bed or crib.

Having described my invention, what I claim is:

1. A crib including in combination a base frame and a crib body vertically adjustable upon the base frame and including a mattress supporting frame, end walls, a side wall, and a second side wall mounted upon the body for movement from a horizontal position beneath the mattress supporting frame to a vertical position coacting with the end walls of the body and vice versa, and bed rail engaging members carried by the crib body but vertically adjustable relative to the body for engaging the body with the side rail of a bed.

2. In a crib in combination a base frame, a crib body vertically adjustably upon the base frame and including a mattress supporting frame, end walls, a side wall, and a second side wall mounted upon the body for

- movement from a horizontal position beneath the mattress supporting frame to a vertical position against the end walls of the body or vice versa, and means for engaging the crib body with a side rail of a bed including downwardly opening hooks having shanks shiftably mounted for vertical movement on the body, the hook being disposed midway of the length of the shank.
- 5 3. A crib having in combination a base frame and a crib body vertically adjustable upon the base frame and including a mattress supporting frame, the crib body having end walls and a side wall, rails mounted upon and extending below the ends of the mattress supporting frame and transverse to the length of the crib and extending upward at their forward ends, and a fourth wall having trunnions resting upon and sliding on said rails whereby the fourth wall may be shifted from a horizontal position resting on the rails beneath the mattress supporting frame to a vertical position coacting with the end walls of the 20 crib body and with the trunnions disposed in the upwardly extending portions of said rails, and means carried by the vertically adjustable crib body for engaging the body with the side rail of a bed, said means being vertically adjustable relative to the crib body.
- 25 4. In a crib, a supporting base, a mattress supporting frame vertically adjustable upon the base and having transverse end members formed with vertically extending eyes at their upper ends, and means for engaging said transverse members with the side rail of a bed comprising downwardly extending hooks, the shank of each hook extending downward below the bill thereof and at its lower end being extended vertically upward to a point above the top of the hook, said rebent shank being slidably engaged in the corresponding eye and being 30 formed with a stop at its upper end.
- 35 5. The combination with a crib having a base frame, a mattress supporting frame having end members and side members and end walls and a side wall, a fourth wall mounted upon the body to swing to a vertical position or into a horizontal position and slide beneath the frame, of means for detachably engaging the crib with a bed rail comprising vertically slidable hooks 40 mounted at the ends of the mattress supporting frame, each hook being downwardly turned and having a vertically extending shank slidably mounted for vertical and rotatable movement on the body, said hook being disposed intermediate the ends of the shank.
- 45 6. The combination with a mattress supporting body including end members, a truck disposed beneath the body and vertically disposed supports mounted at each
- end of the truck and engaging against each end of the body, of means detachably engaging the body with said vertical supports at any desired elevation of the body relative to the truck, and means for preventing any accidental dropping of the body relative to the truck and comprising members mounted upon the body at each end thereof and operatively engaging the truck and permitting the free upward movement of the body but preventing downward movement thereof when in operative position, said members being independently manually shiftable into an inoperative position to permit the lowering of the corresponding end of the body.
- 50 7. A crib including a mattress supporting frame having end members, a base frame including longitudinal angle irons, members extending transversely of the longitudinal angle irons and mounted thereon, upwardly extending slotted guides mounted upon the ends of said irons and slidably engaging with the end members of the body, binding screws passing through the slots of the guides and into the end members, and means for holding the body in raised position relative to the base frame comprising serrated bars disposed at opposite ends of the body, each 55 bar being curved downward and inward and having its free end normally extending over the adjacent transverse member, the under edge of each bar being serrated, the upper end of the bar having laterally and upwardly extending ears, and a medially disposed, outwardly extending handle, the extremities of the ears being formed with open knuckles, and a pintle attached to each end member and passing through said 60 knuckles upon which the corresponding bar swings, said bar being detachable from the pintle upon a removal of the corresponding transverse member of the base frame to permit the bar to swing downward, each 65 transverse member being provided with a slotted eye through which the corresponding serrated bar passes and with which the serrations of the bar have engagement.
- 70 8. A crib including a mattress supporting body, a supporting frame therefor disposed beneath the body, a pair of vertically disposed members carried by the supporting frame at each end of the frame and between which pairs of members the mattress supporting body is vertically shiftable, means for detachably engaging the mattress supporting body with said vertical members to thereby hold the mattress supporting body at any desired elevation, and means for preventing the accidental dropping of the mattress supporting body comprising pivoted serrated members mounted upon the opposite ends of the mattress supporting frame and extending beneath said frame, the ser-
- 75 80 85 90 95 100 105 110 115 120 125 130

rated edges of said members operatively engaging against portions of the supporting frame, said members being shiftable out of engagement therewith to permit the lowering of the body.

9. A crib including a mattress supporting frame having end members, a base frame including cross members, vertically extending guides carried by the base frame and between which the body is guided, set screws passing through said guides and into the ends of the mattress supporting frame whereby the mattress supporting frame may be held in any vertically adjusted position upon said guides, and means for holding the body in vertically adjusted positions against accidental downward movement comprising curved bars having serrated outer edges swingingly mounted upon the ends of the mattress supporting body and extending downward and beneath the body, the cross members of the supporting frame having guides through which said members pass and with which the serrations of the bars engage, and means mounted on the bars whereby they may be manually lifted from engagement with said guides to permit the lowering of the frame.

10. A crib including in combination a base frame, a crib body vertically adjustable upon the base frame, including a mattress supporting frame having end walls, a side wall, and a second side wall mounted

upon the body for movement from a horizontal position beneath the mattress supporting frame to a vertical position against the end walls of the body and vice versa, and means for engaging the crib body with a side rail of a bed including downwardly extending hooks mounted for vertical shifting movement upon the body, said hooks being shiftable to a level above the point of attachment of the hooks to the body or to a level below said point of attachment.

11. A crib including in combination a crib body supported for vertical adjustment, said body having a mattress supporting frame, end walls, a side wall, and a second side wall mounted upon the body for movement from a horizontal position beneath the mattress supporting frame to a vertical position coacting with the end walls of the body and vice versa, and means for engaging the crib body with a side rail of a bed including bed rail engaging members mounted for vertical, shifting movement upon the body, said members being shiftable to a level above the point of attachment of the members to the body or to a level below said point of attachment.

In testimony whereof I hereunto affix my signature in the presence of two witnesses.
